TRIGGER

Russell Wiles, Chicago, Ill.; Ethel Foster Wiles,
executrix of said Russell Wiles, deceased, as-
signor to Ethel Foster Wiles

Application July 9, 1943, Serial No. 493,959

13 Claims. (Cl. 42—69)

This invention is a trigger and is described herein and illustrated in the accompanying drawing, in which:

Figure 1 is a longitudinal section (partly in elevation) of a rifle action including the trigger; Figure 2 is a graph showing the characteristics of the type of spring used, and for contrast those of an orthodox spring; Figure 3 is a graph illustrating the characteristic of the trigger in different applications; and Figures 4-7 are diagrammatic representations of the triggers graphed in Figure 3.

Good triggers may have a preliminary safety pull or slack as found in e. g. the U. S. Army rifle Model 1903 (Springfield), or this slack may be omitted as in most arms made for civilian use, e. g. the Winchester 52 target rifle. In either event, after the slack is taken up, if there is slack, the trigger in the trigger pull proper should not move at all until the required force is applied, and it should then move instantly and rapidly through the whole releasing movement (like breaking a small glass rod) and should be positively arrested or stopped as soon as possible to eliminate "back-slap."

The major difficulty in trigger action is drag. In weapons of the highest grade with small tolerances, the overlap of the disengaging surfaces may be made so small, and the surfaces may be honed so smooth that drag is quite imperceptible. First class triggers are quite customary in the best arms. However, even the best arms often wear so that the necessary trigger weight is lost or the surfaces wear rough so that the drag becomes objectionable. In cheaper arms a considerable overlap of the disengaging surfaces is required to meet necessary tolerances, and these surfaces are often so rough initially, or wear so rough in use, that the pull is usually poor. A skilled marksman applies pressure to the trigger very gradually, so that when the trigger starts, he is exerting no more pressure than is needed, so that a rough spot in the surfaces is often quite enough to stop the disengaging movement until more pressure is applied. Thus poor triggers move in a series of jumps and not only make accuracy difficult, but often cause bad shooting habits.

The present trigger attains the desired let-off by employing, as at least a part of the force which resists disengagement, a spring means whose force-displacement curve has a portion with a negative slope, and precompressing or pre-displacing the spring so that the major part, preferably all, of the disengaging movement of

the trigger occurs against a spring force less than that required to start its movement.

A common spring possessing the characteristics required is the disc type of spring forming the bottom of an oil can. Disc springs of this type have been highly developed in the thermostat art, where, when made of bimetal, they are commonly called Spencer discs. And numerous types of springs having similar characteristics are well known. No attempt will be made to enumerate all the types, but among them are springs known as the confined-arch type, springs which are curved in one plane and under pressure buckle and curve as a plane at right angles, corrugated disc springs, and many others.

Figure 2 is a graph showing force as ordinates and displacement as abscissae. All the curves naturally start at the origin where force and displacement are zero. The line A, by way of contrast shows the characteristics of a conventional spring, e. g. a helical spring, where force and displacement are linearly proportional.

The curve B shows the characteristics of the preferred type of spring. It rises from the origin like the curve of a conventional spring, but presently flattens out, reaching a peak at b, descending with a negative slope to a minimum at b' and then rising on a second positive slope. A study of this curve demonstrates that if the spring is displaced by a force such as that exerted by a screw, it will move gradually through its whole course, the back pressure against the screw at each point of displacement being represented by the ordinate at that point.

But if displacement be effected by a following-up force like a weight, or like a long helical spring where pressure is nearly as high at the end as at the beginning of the displacement, or like the elastic muscles and tissues of the trigger finger where pressure on the trigger is nearly as great at the end as at the start of its short movement, then when the spring is deflected just past the peak b of the curve, it will snap swiftly through the trough of the curve to a point b² on the second position slope where the force required to effect further deflection again equals that exerted at the peak.

And during the entire snap movement the pressure required to keep the spring in motion is well below that actually exerted on it at the peak, so that when used as a trigger spring, the excess force will sweep past any rough spots so that they will not be felt.

To get the best results, the spring should be so mounted that it is precompressed or pre-

deflected to a point such as b^3 below the peak on the negative slope. Then it cannot move at all until a force represented by the ordinate of that point is applied, and when such a force is applied by a follow-up elastic pressure, as by the finger, the entire movement is of the snap type.

The spring selected should have a steep enough negative slope that the spring force falls so fast that no rough spot on the engaging surfaces can raise the force to that required to start the movement. The length of the snap movement should be long enough to complete the disengagement before the force has risen very far on the second positive slope of the curve. Furthermore, the spring mount should have a stop so that extra hard pressure on the trigger cannot break or strain the spring so as to modify the trigger pull.

Referring now to Figure 1, the spring (disc type) is shown applied to the well known Winchester 52 of the latest type. In this action 11 is the striker held in cocked position by the sear 12 pressed up by the sear spring 13 and held up by the engagement of the surface 14 on the trigger 15 with the surface 16 on the sear 12. On closing the bolt, the heavy spring 17 at the rear of the sear is compressed so that this spring forces the sear out of engagement with the striker when the movement of the trigger permits. The surfaces 14 and 16 on trigger and sear are the disengaging surfaces whose relative movement controls the discharge of the piece. All the above parts and operations are well known.

The trigger spring is the disc 18 set in the cylindrical mount 19. Through the head 20 of this mount extends a flanged button 21, one end of which bears on a stud 22 on the trigger and the other end of which bears on the spring 18. The opposite end of the mount 19 is closed by a threaded slightly dished plug 23 which operates as a spring stop to prevent straining the spring, and to arrest the movement of the trigger when disengagement is completed. For purpose of clarity the curvatures of the precompressed spring and the plug are somewhat exaggerated in the drawing, permitting a trigger movement longer than required to disengage. In practice the spring throw is, as stated, so short as to arrest the trigger when disengaged. The plug is preferably perforated so that suction will not delay the return of the spring.

The spring is calibrated and adjusted as follows. Let us assume that, in view of the leverage, the spring should snap at 4 lbs. Springs are made to have a peak of the pressure deflection curves at say 4.8 lbs. Absolute uniformity will be difficult to attain, but variation will not be very important. The spring in its mount is located for adjustment with the button 21 up and a 4 lb. weight is applied to the button. This is not enough to deflect the spring past the peak of the curve. The plug 23 is then screwed in. This first presses the spring up until the flange on the button contacts the head 20 of the mount, and then further deflects the spring (flattening it) until its force passes the peak and descends on the negative slope to a point where it snaps under the 4 lb. weight. The spring is then adjusted exactly to the desired pressure.

In many types of locks the spring so mounted and adjusted can be fixed in any appropriate place to resist disengagement. But in the Winchester 52 lock, the sear acts also as the bolt stop and to release the bolt for cleaning must be

greatly depressed by an extra long powerful movement of the trigger. To permit this movement, the spring mount is slidably set in a cylinder 24 and pressed down by a heavy spring 25 against a threaded collar 26 by which the button 21 is adjusted to contact the stud 22 on the trigger.

On the application of the heavy pressure required to depress the sear for bolt removal, the spring mount moves up bodily against the spring 25 whose pressure is so high that, in firing, the trigger is effectively arrested when the spring strikes the dished face of the plug 23.

Consideration will now be given to the characteristics of the lock to which the present spring may most advantageously be applied. For clarity reference is made to Figure 3, which illustrates the characteristics of several locks, and to Figures 4-7, which represent the trigger diagrammatically. In Figure 3, and in the diagrams, friction is ignored, and for clarity the trigger spring leverage is assumed to be 1:1 so that to get a 4 lb. trigger pull we use a 4 lb. resistance. These assumptions greatly aid clarity and simplicity of description.

First let us assume a lock, Figure 4, which inherently interposes a constant 2 lb. resistance to disengagement. This resistance may result either from the angle of the disengaging surfaces 14 and 16, particularly 16, or from the presence of a constant pressure trigger or sear spring resisting disengagement as in the case of the U. S. Army rifle Model 1903 (Springfield) during the safety pull or "taking up the slack," or it may be a result of both. It is represented in Figure 4 by the arrow marked 2 lbs.

In Figure 3, the horizontal line D represents this constant force resisting disengagement. Now let us arbitrarily assume that the negative slope spring selected has its first maximum at 2.4 lbs. and its minimum at 0.6 lb., i. e. the force at the minimum is $\frac{1}{4}$ of that at the first maximum. Obviously the installation of such a spring pre-deflected to 2 lbs. will give a trigger pull with the characteristics shown by the curve D' which is simply the curve of the spring added to the inherent 2 lb. constant resistance. The peak of the curve will be at 4.4 lbs., but, because of the predeflection, movement will start at 4 lbs., and the minimum pull will be 2.6 lbs. (2 lbs. + 0.6 lb.). The negative slope will be as shown.

Next assume a lock with zero inherent resistance to disengagement. In the piece shown in Figure 1, this can be accomplished by grinding the disengaging surfaces, especially the surface 16 on the sear at the angle of repose for steel surfaces. Obviously, such a trigger will theoretically stay engaged if no force is applied, but will move with a very light pressure. To get the desired 4 lbs. pull we may assume we use two disc springs, set together in parallel to give double force. This in some respects is a desirable way to get high spring pressures, because should one disc crack from fatigue, the lock will still operate, but with a lower trigger pull. This arrangement is shown diagrammatically in Figure 5.

Under these conditions the Line D² shows the inherent resistance of the trigger to disengagement (zero) and the curve D³ shows the actual characteristics of the trigger pressure in its mount. The peak of the curve is 4.8", and the minimum is 1.2 lbs. The double spring is pre-deflected to start its snap movement at 4 lbs. on the negative slope as before. This curve D³ has a steeper negative slope.

A third condition, diagrammed in Figure 6, is where the disengaging surfaces, especially that on the sear, are ground below the angle of repose so that, in the absence of a trigger or spring, sear spring or the like, the trigger will automatically be forced out of engagement. The Birmingham small arms Martini action is usually ground this way, so that, if the trigger spring breaks, and the piece is cocked, while manually holding the trigger forward, the striker or firing pin will fall as soon as manual pressure is released, since the trigger is subjected to a constant negative, or disengaging force which is overcome only by the heavy trigger spring which normally holds the tip of the trigger under the shoulder on the tumbler. This disengaging force may be represented diagrammatically by the arrow marked "-2 lbs." in Figure 6.

Let us assume the negative or disengaging force inherent in the trigger is 2 lbs., as indicated by the horizontal line D⁴ representing a constant force of -2 lbs. Now to get a trigger pull of 4 lbs. we may take three discs piled together in parallel and the actual characteristics of the trigger will be represented by the curve D⁵ whose peak is 5.2 lbs., predeflected as before to give a starting pressure of 4 lbs., and whose minimum is -0.2 lb. This curve not only has a very steep negative slope adequate to overcome the added resistance of very rough spots in the drag, but at its minimum is actually tending to move by itself with no finger pressure at all. The snap action is then very rapid. In this case the negative force must be in part, at least, exerted through the engaging surfaces so that, on disengagement it ceases to exist, at least to such an extent that the trigger will return to normal position for re-cocking the piece.

While the preferred spring has a steep negative slope, and is predeflected so that its movement starts on the negative slope to the end that roughnesses even in the very start of the drag are rendered harmless, yet it will be appreciated that, during the first positive slope of its curve the spring acts as an ordinary conventional trigger spring, and is just as good in every respect. Furthermore, roughnesses in the drag most often develop toward the end of the drag where the engaging areas are reduced and the higher unit pressures tend to produce the greatest wear. Hence, trigger action superior to the conventional action, but inferior to the preferred action can be obtained by predeflecting the spring to the peak of its curve or to a point just below the peak on the first positive slope. The trigger will then act like a conventional trigger during the first part of its movement when roughnesses in the drag are less likely to occur, and will snap after the short conventional movement so as to overcome any rough spots toward the end of the trigger movement. This is a less efficient use than the preferred one wherein trigger movement starts on the negative slope and through its whole movement requires less force to move it than was required to start it.

Referring again to Figure 2, the curve C shows the characteristics of another spring which may be used. Like the other curves, this starts at the origin, rises at first like the curve of the conventional spring A, flattens off to a maximum c, falls to a minimum c', and again rises on a second positive slope. But this curve crosses the line of zero force at c² and rises to intersect it again at c³. A spring of this type snaps as before when deflected by a following-up force but,

since its force falls below zero, it will not return to normal on the release of pressure but instead stops at the point c³ and will only return if forced back. If a reverse following-up force is applied to drive the spring back from the point c³ to the minimum c', it will snap back. Such springs have known uses in the arts.

A spring of these characteristics may be used by selecting a spring with a comparatively long throw and arresting its movement by a positive stop at a point such as c⁴ on the negative slope above zero force. If the spring is predeflected to the point c⁵, and arrested by the stop at the point c⁴, the effective snap movement is that between these points.

Evidently it is theoretically possible to use a spring with the characteristics of curve C, let it snap below zero, and return it by some mechanical action. This would probably be too complex for practical use.

Further, it is known (see Spencer Patent No. 1,972,172) that a spring with the characteristics of curve B (Figure 2) is in reality the same in essence as one represented by curve C plus a bias which keeps the curve at all times above zero force. This bias is most conveniently imparted as a set of the metal in manufacture, but it may also, as shown in said Spencer patent, be imparted by a separate conventional spring. Hence, a composite spring may be the operative equivalent of a spring represented by curve B, although less desirable from a manufacturing standpoint.

It is also shown in said Spencer patent that a reverse snap action occurs, when a snap action spring returns to position under the influence of a conventional spring pushing against it. In this case, diagrammed in Figure 7, the resultant negative slope spring action is the force of the conventional spring (assumed to be constant through the small throw of the trigger) less the rapidly rising force of the disc spring in its return movement. In this case the disc spring is held precompressed to its point of minimum force by the heavier conventional spring, the resultant at this point being 4 lbs. As the trigger starts against the conventional spring, the snap of the disc helps it along with a constantly rising force, the resultant of the composite at all points being the force of the conventional spring less that of the disc. This curve is not graphed but it may coincide closely with the negative slope part of curve D.

The spring is herein illustrated as of the disc type because these are easily available and their operation is well known. In the rifle selected to illustrate the invention there is ample space for the installation of this spring.

However, in many actions, the lateral thickness of the weapon may make it desirable, for the purpose of reducing lateral dimension, to use a spring of similar characteristics but narrower. A spring, for example, of the confined arch type suggests itself as readily adaptable to narrow spaces.

The foregoing detailed description has been given for clearness of understanding only, and no unnecessary limitations should be understood therefrom, for some modifications will be obvious to those skilled in the art.

I claim:

1. In small arms, a spring impelled firing member which on movement from cocked position causes the discharge of the arm, a finger-controlled member, means operatively connecting the finger-controlled member with the firing mem-

ber, said means including two surfaces adapted to be disengaged, the first of which is moved by the finger-controlled member to release the second, and spring means resisting the disengaging movement, said spring means being of the type whose force deflection curve has a portion with a negative slope and being arranged to resist disengagement with a force which decreases during the disengaging movement.

2. A device according to claim 1 in which the spring means at the start of the disengaging movement exerts at least sufficient force to supply the necessary trigger pull weight.

3. A device according to claim 1 in which the surfaces are so related that except for the spring means, they will disengage and in which the spring means exerts the force required to prevent disengagement and to give in addition the necessary trigger pull weight.

4. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, and spring means resisting the disengaging movement, said spring means being of the type whose force deflection curve has a portion with a negative slope and being arranged to resist disengagement with a force which decreases from the start of the disengaging movement and which throughout disengagement is less than at the start of disengagement.

5. A device according to claim 4 in which the spring means at the start of the disengaging movement exerts at least sufficient force to supply the necessary trigger pull weight.

6. A device according to claim 4 in which the surfaces are so related that except for the spring means they will disengage and in which the spring means exerts the force required to prevent disengagement and to give in addition the necessary trigger pull weight.

7. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, and spring means resisting the disengaging movement, the spring means being of the type whose force deflection curve rises to a maximum and descends therefrom with a negative slope, the spring means being predeflected to a point past said maximum so that its initial deflection under disengaging pressure is in the range of falling force.

8. A device according to claim 7 in which the spring means at the start of the disengaging movement exerts at least sufficient force to supply the necessary trigger pull weight.

9. A device according to claim 7 in which the surfaces are so related that except for the spring means, they will disengage and in which the spring means exerts the force required to prevent

disengagement and to give in addition the necessary trigger pull weight.

10. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, a spring of the type whose force deflection curve rises to a maximum and then descends with a negative slope, a mount for the spring, means in the mount to predeflect the spring, and means operatively connecting the spring to the first surface to resist its disengaging movement.

11. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, a spring of the type whose force deflection curve rises to a maximum and then descends with a negative slope, a mount for the spring, means in the mount to predeflect the spring, and means operatively connecting the spring to the first surface to resist its disengaging movement.

12. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, a spring of the type whose force deflection curve rises to a maximum and then descends with a negative slope, a mount for the spring, means in the mount to predeflect the spring, and means operatively connecting the spring to the first surface to resist its disengaging movement, and means in the mount to limit the deflection of the spring.

13. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, a spring of the type whose force deflection curve rises to a maximum and then descends with a negative slope, a mount for the spring, means operatively connecting the spring to the first surface to resist its disengaging movement, and means to adjust the position of the mount.

14. In small arms, a spring impelled firing member which on movement from cocked position causes the discharge of the arm, a finger-controlled member, means operatively connecting the finger-controlled member with the firing member, said means including two surfaces adapted to be disengaged, the first of which is moved by the finger-controlled member to release the second, a spring of the type whose force deflection curve rises to a maximum and then descends with a negative slope, a mount for the spring, said mount being movable, means in the mount to predeflect the spring, means operatively connecting the spring to the first surface to resist its disengaging movement, and resilient means normally resisting bodily movement of the mount but providing for movement thereof under pressure markedly heavier than that exerted in disengagement.

RUSSELL WILES.
